Herbert F. Diegel, 1524 E. Culver St.,
Phoenix, Ariz. 85006

Filed Nov. 5, 1971, Ser. No. 196,247

Term of patent 14 years

Int. Cl. D16—04

U.S. Cl. D61—1 P

FIG. 1

FIG. 2

FIG. 1 is a front perspective view of a photo print carrier showing my new design, the rear being a mirror image thereto;

FIG. 2 is an enlarged sectional perspective view of the handle/clasping means therefor;

FIG. 3 is a rear perspective view of FIG. 2.

I claim:

The ornamental design for a photo print carrier, as shown and described.
